UNITED STATES PATENT OFFICE.

JOHN O. HOBBS, OF CHICAGO, ILLINOIS.

STARTING DEVICE FOR ENGINES.

1,150,033.

Specification of Letters Patent. Patented Aug. 17, 1915.

Application filed February 1, 1912. Serial No. 674,663.

To all whom it may concern:

Be it known that I, JOHN O. HOBBS, a citizen of the United States, residing at Chicago, in the county of Cook and State of Illinois, have invented certain new and useful Improvements in Starting Devices for Engines, of which the following is a specification.

My invention relates to explosive engines in general, but more particularly to starting devices for the engines of automobiles.

In order to start an explosive engine it is necessary to give to the crank shaft an initial rotation of sufficient extent to compress and then to ignite a charge of the explosive mixture in the cylinders. Usually this is done by hand by means of a crank attached to the end of the crank shaft of the engine. This necessitates the leaving of his seat by the operator and requires considerable effort on his part to give to the shaft the necessary initial movement.

The object of my invention is to provide a device operated by fluid pressure which will impart to the crank shaft the necessary preliminary rotation and to start the explosions.

A special feature of my invention is a cylinder containing a plunger which gives rotation to the crank shaft by means of a chain or other flexible element which is attached to the plunger at one end and to the crank at the other, the chain being partially wound upon said crank in its normal position.

A further feature of my invention consists of a fluid pressure operated clutch so combined with the above described starting mechanism that it will cause the crank to become drivably attached to the shaft during the period of action of the starting device and to be disconnected therefrom when the operation of starting has been completed.

A further object of my invention is to provide a fluid pressure operated starting device for explosive engines which will be simple in construction and efficient and convenient in operation.

Other objects will become more fully apparent in the following specification when taken in connection with the accompanying drawings, in which—

Figure 1 is a front elevation partly in section. Fig. 2 is a vertical section taken along

the line 2—2 of Fig. 1. Fig. 3 is a sectional view of the valve mechanism showing the valves in certain operated positions.

Similar reference characters are used to designate similar parts in the several figures of the drawings.

The engine shaft is represented by the reference numeral 10 and fixed thereto is a disk 11. Adjacent this disk is another clutch element or disk 12 which is loosely mounted upon said shaft and which is clutched to said disk 11 during the period of operation of the starting device as will be more fully described below.

A plunger 13 is given a rectilinear movement in the cylinder 14 by fluid pressure, this pressure being transmitted to the clutch element by means of a chain 15. The chain 15 is fixed at one end to said clutch element and to the stem of the plunger 13 at its other end. The chain is partly wound about the circumference of the circular member 46 attached to said clutch element 12.

A valve 16 controls the flow of air from a reservoir 18 to the starting device. A pipe 19 leads from said reservoir to said valve. A handle 20 is attached to said valve. The port 21 leads diametrically through said valve and registers with the ports 22 and 23 in the casing thereof when the valve has been thrown to its starting position, as shown in Fig. 1. A pipe 24 leads from this valve to the head of the starting cylinder and connects with a channel 25 in said head. Said valve with its handle 20 may be located within convenient reach of the operator of the automobile and for that reason may be attached to the body by any suitable means. The pipe or tube 24 may be of considerable length and disposed in such a manner as will harmonize with the body structure.

The channel 25 divides into two other channels 26 and 27 in the head of the cylinder. The channel 26 leads into the cylinder while the channel 27 leads to a valve 17, fitted preferably into the head of the cylinder. A channel 28 leads diametrically through said valve and registers with a port 28^a in the wall thereof to which is connected a pipe 29 leading to the clutch previously mentioned. This valve is automatically actuated, as will be described later, while the valve 16 is operated manually.

The valve 16 is provided with a port 30,

preferably disposed at right angles to the port 21. The port 30 is adapted to register with the port 23 when the handle 20 is moved to its normal position indicated by 5 the dotted lines 32. When the valve has this position the port 21 registers with the exhaust port 31. In this position the port 23 is open to the outside air, while the port 22 is closed. In the normal position of the 10 valve, therefore, the fluid pressure from the clutch and the cylinder will be released. The valve 17 in like manner is provided with a port 33 having a position preferably at right angles to the port 28. The port 33 15 is adapted to register with the port 28^a when the valve is thrown to its operated position in the automatic release of the pressure from the cylinder, this position of the valve being indicated in Fig. 3. The port 20 28 then registers with the exhaust port 34. The fluid pressure in the clutch will then be free to escape.

The valve 17 is provided with an operating lever 35 to which is pivotally attached a 25 connecting rod 36 leading to a lever 37. This lever is pivotally mounted on the cylindrical portion 38 of the frame member 54. This lever 37 is actuated by a pin or lug 39 carried by the clutch member 12. The pin 30 39 strikes the lever after the predetermined extent of movement has taken place and then carries said lever forward until the valve 17 has reached its release position. A pin 39^a on the plunger stem may be substituted for 39. A buffer 60 is suitably located to receive the blow of the lug 61 carried by the clutch member 12. A spring 40 is attached at one end to said lever 37 and at the other end to any suitable fixed member, such 40 as the pin 41. The function of this spring is to restore the lever 37 to its normal position and hence the valve 17 to its original position. The lever 37 is also provided with a handle 42 at its end to permit its manual 45 operation.

The chain 15 is attached at one end by a pin 43 to the disk 46. I preferably turn a pair of the links of the chain at right angles to the chain and pass said pin through 50 them and through said disk. In a similar manner I attach the other end of the chain to the plunger rod 45 by means of a pin 44. The plunger rod 45 is preferably a T-bar, its central web serving as a convenient 55 means for the attachment of the chain while its head serves as a bearing for a guide roller 49. The disk 46 is preferably fixed to the clutch member 12 by means of posts 48 which are integral with said clutch member 60 and by screws 47 which are threaded into said posts. A spring 55 is attached to the disk and clutch member at one end, as shown at 56, and to the fixed member 38 of the frame as shown at 57.

65 The clutch member 12 carries a flexible

disk 52 of suitable flexible material, such as leather, which bears upon the crank disk 11. Fluid pressure is admitted to the space 51 between the clutch member 12 and the disk 52 through a flexible hose or conduit 50, which is joined to the pipe 29.

In the operation and use of my invention the operator first rotates the valve 16 from the normal position shown by the dotted lines 32 to the position shown in solid lines 75 in Fig. 1. This permits the fluid pressure to flow from the reservoir 18 through the ports 22, 21, 23, pipe 24 and channel 25 where it divides and passes through channel 26 to the cylinder and channel 27 to the 80 clutch. In the normal position of the parts the valve 17 has the position shown in Fig. 1 thereby allowing the fluid to pass through the port 28. The arm 35 and lever 37 will have the position shown in Fig. 1. The fluid pressure having entered the space 51 will cause the disk 52 to engage the disk 11 and the friction thereby resulting will enable the clutch member 12 to drive the crank disk 11. The pressure having entered the cylinder behind the plunger 13, the chain 15 will be placed under tension and rotation of the disk 46 will be effected and hence the clutch member 12 will be also rotated. Rotation will continue until the pin or lug 39 strikes the 90 lever 37 after which said lever will be carried along until the valve 17 is rotated sufficiently to cause the port 28 to come into register with the outlet port 34. Simultaneously therewith the port 33 will come into 95 register with the port 28^a and the fluid in the space 51 in the clutch will be released. The clutch will thereby become disengaged and the engine shaft will be free to continue 100 its rotation without carrying the clutch member 12 with it. When the clutch member 12 has thus become disengaged it will be free to return to the normal position, which it will do because of the tension of the spring 55. The disk 46 and pin 39 will 105 clearly be carried with it. The spring 40 will cause the lever 37 to return to its original position and the valve arm 35 by means of the connecting rod 36 will be restored to its original position. The reverse rotation 110 of the clutch member 12 and disk 46 will cause the chain 15 to become rewound thereon and this in turn will cause a return stroke of the plunger stem 45 and the plunger 13. At the instant of release of the fluid from 115 the clutch, the operator will restore the valve arm 20 to its normal position which will place the port 21 in register with the outlet port 31 and the port 30 in register with the port 23, thereby permitting the release 120 of the fluid from the cylinder and permitting the full return of the plunger 13. The operation above described will, of course, take place very quickly and the operator 125 will find it necessary and convenient to re- 130

store the valve arm 20 to its normal position almost immediately after he first operates it to effect the starting action.

While my improved starting mechanism is very largely automatic in its character, it will be seen to be sufficiently subject to manual operation to cause it to be fully under the control of the operator. My improved chain connection between the plunger and the crank clutch affords a very effective and practical means for transmitting the rectilinear motion of the plunger to the rotatable engine shaft. The difficulties encountered heretofore with rack and pinion mechanism are thereby obviated.

While I have described my invention more or less precisely as regards the details of construction, I do not wish to be understood as limiting myself thereto, as I contemplate changes in form and the proportion of parts and the substitution of equivalents as circumstances may suggest or render expedient without departing from the spirit of my invention.

I here make cross reference to my co-pending application, Serial No. 668,114, filed December 27, 1911, which relates to a starting device for explosive engines, differing in some respects from the device disclosed herein.

I claim:

1. In a starting device for explosive engines, the combination with a shaft, of a crank loosely mounted on said shaft, a cylinder and piston, a flexible power transmitting element connecting said piston to said crank, a source of elastic fluid under pressure, a clutch to connect said crank to said shaft, means to operate said clutch by elastic fluid under pressure, means to admit and to shut off the admission of elastic fluid under pressure from said source simultaneously to said cylinder and said clutch operating means, automatic means for disengaging said crank from said shaft after a predetermined extent of movement of said shaft has taken place, and a spring to restore said parts to their normal condition.

2. In a starting device for explosive engines, the combination with a shaft, of a crank loosely mounted upon said shaft, means for applying fluid pressure to said crank, a fluid pressure operated clutch for locking said crank to said shaft, means for simultaneously controlling the application of fluid pressure to said crank and clutch and for releasing the fluid pressure from said crank, and automatic means for releasing the fluid pressure from said clutch.

3. In a starting device for explosive engines, the combination with a shaft, of a crank loosely mounted upon said shaft, means for applying fluid pressure to said crank, a fluid pressure operated clutch for locking said crank to said shaft, a manually

operated valve mechanism for simultaneously controlling the application of fluid pressure to said crank and to said clutch and automatic valve mechanism for releasing the fluid pressure from said clutch. 70

4. In a starting device for explosive engines, the combination with a shaft, of a crank loosely mounted upon said shaft, means for applying fluid pressure to said crank, a fluid pressure operated clutch for locking said crank to said shaft, valve mechanism for controlling the application of fluid pressure to said crank and to said clutch, means for manually operating said valve mechanism to apply fluid pressure to said crank and to said clutch and to release said fluid pressure from said crank, and means automatically actuated by said crank for releasing the fluid pressure from said clutch. 85

5. In a starting device for explosive engines, the combination with a shaft, of a crank mounted on said shaft, a flexible member attached to said crank, means for applying power to said flexible member and thereby to rotate said shaft, means for automatically restoring said crank and flexible member to their normal positions, and automatic means for disconnecting said crank from said shaft after a predetermined extent of 95 movement has taken place.

6. In a starting device for explosive engines, the combination with a shaft, of a crank loosely mounted on said shaft, a flexible member attached to said crank, means for applying power to said flexible member and thereby to rotate said shaft, means for simultaneously locking said crank to said shaft, means for restoring said crank and flexible member to their normal positions, 100 and means for automatically permitting the unlocking of said crank from said shaft after a movement of a predetermined extent has taken place. 105

7. In a starting device for explosive engines, the combination with a shaft, of a crank loosely mounted upon said shaft, a flexible member attached to said crank, a plunger connected with said flexible member, a cylinder containing said plunger, a clutch 110 for locking said crank to said shaft, means for supplying fluid pressure to said cylinder and simultaneously operating said clutch to lock said crank to said shaft and for releasing the fluid pressure from said cylinder, 115 and means for independently releasing the pressure from said clutch. 120

8. In a starting device for explosive engines, the combination with a shaft, of a disk fixed upon said shaft, a disk loose upon said shaft adjacent said fixed disk, a flexible clutch member rigidly secured to said loose disk and adapted frictionally to engage said fixed disk, means for applying power to said loose disk and simultaneously admitting 125 130

fluid pressure to the space between said loose disk and said flexible clutch member and for discontinuing the application of power to said loose disk, and means for independently discontinuing the admission of fluid pressure to the space between said loose disk and said flexible clutch member.

9. In a starting device for explosive engines, the combination with a shaft, of a disk
10 fixed upon said shaft, a disk loosely mounted upon said shaft adjacent said fixed disk, a flexible clutch member rigidly secured to said loose disk and adapted to frictionally engage said fixed disk, a flexible member attached to said loose disk at one end, a plunger attached to said flexible member at its other end, a cylinder in which said plunger reciprocates, manually operated means for simultaneously supplying fluid pressure to
15 said cylinder and to the space between said flexible clutch member and said loose disk and for subsequently releasing fluid pressure from said cylinder, and automatic means for independently releasing fluid pressure from said space.
